BY *John J. Mack*
ATTORNEYS.

UNITED STATES PATENT OFFICE.

VERSAL V. VAUGHN, OF LOS ANGELES, CALIFORNIA.

TRIMMING TOOL.

Application filed November 1, 1926. Serial No 145,495.

This invention relates to and has for a main object the provision of an improved type of tool which is adapted for cleaning the surface of storage battery terminals such as are used in motor cars and in connection with radio sets, and for other purposes, whereby the terminals which generally corrode to a large extent can be cleaned and resurfaced quickly and nicely.

Another object is to provide an improved type of tool over that shown in my pending application for trimmers, filed Oct. 19, 1926; Serial Number 63,346.

It is a further object of the present invention to provide an improved tool having the general form and characteristics of a pair of pliers, arranged with a trimming tool mounted on one of the handles thereof, and provided with a tapered cutting edge formed so as to embrace a battery terminal in such a manner that the cutting edge will be resiliently held against the tapered terminal, and will conform itself to the size of the terminal, whereby when rotated about the terminal the outer surface thereof will be trimmed preparatory to attaching the usual connectors thereto.

Another object is to provide in a tool of the character described, in connection with a pair of pliers for supporting the tool on the handle thereof, jaws formed on opposite ends of the plier halves and provided without receiving notches, whereby the same tool may be employed as a wrench for removing and attaching nuts from and to the connector bolts, respectively.

Other and more detailed objects of invention will appear as the description progresses.

I have shown a preferred embodiment of my invention in the accompanying drawing, in which:

Fig. 1 is an elevation of a battery with a terminal thereon, and my improved tool shown in operative relation thereto.

Fig. 2 is a substantially full-sized view of my complete tool.

Fig. 3 is an enlarged side view of the wrench jaws of the same.

Fig. 4 is a transverse section on line 4—4 of Fig. 1; and

Fig. 5 is a perspective view of the trimming tool attached to the pliers shown in Fig. 1.

In the consideration of this invention, it will be understood that the usual battery terminals *t* are of larger diameter at their lower

extremities than at their upper extremities, in order that connectors of different size, by means of which the wires are attached to the battery, may be frictionally held on the terminals. Accordingly, I have provided a tool which is tapered corresponding to the taper of the terminals *t*, and formed of tempered spring steel provided with a single cutting edge at the end of an arcuate portion, which is formed on a radius less than the radius of the terminal *t*.

The terminal trimming tool is adapted to be mounted on a well-known form of tool, as shown in Fig. 1, composed of substantially like portions *A* and *A'*, with enlarged body portions *a* and *a'* respectively, pivotally held together by means of a rivet or bolt *P*, and formed with extended handles *H* and *H'* and jaws *J* and *J'*, respectively, on opposite sides of the pivot *P*.

The trimming tool *T* is formed of a single piece of tempered spring steel, with a slightly curved attaching portion *b*, having perforations *o* therein adapted to abut the end of the handle *H* or *H'*, and to be secured thereto by means of one or more rivets or screws, as at *r*. The slight arc formed in the portion *B* of said tool serves substantially as a lock washer so that the tool *T* will be held in tension and against accidental removal from the handle *H*.

Forwardly of the portion *b* a short extension *g* is provided which flares outwardly to a slight extent, and on the opposite side portion *b* is continued in a side portion *d*, which joins with an arcuate portion *f* formed on a radius which is less than the radius of the terminal *t*. The arcuate portion *f* terminates in a cutting edge *e*, which is substantially spaced from the edge *e'* of the portion *g* and is adapted to engage the outer surface of the battery terminal *t* when the device is in use.

The cross section of the tool *T*, as shown in Fig. 4, is such that the terminals *t* will have a bearing on the portion *d* at a point on the periphery of the terminal *t* and also at other peripheral points on the edges *e* and *e'*. The opening between the edges *e* and *e'* is so positioned that said edges will touch the periphery of the terminal *t* at equally spaced points from and on opposite sides of a transverse line cutting the axis of the terminal *t*, as indicated in Fig. 4, while the arcuate portion *f* of the tool will be disengaged from the surface of the terminal as will also be the

attaching portion *b*. The portions *d*, *f*, and *g* of the tool *T* are tapered throughout the length thereof so that the tool at the bottom will be of slightly larger area than at the top, 5 the taper thereof conforming, as herein stated, to the taper of the terminal *t*.

As shown in Fig. 1 the pliers comprising the pivotally connected portions *A* and *A'* are held in the hand vertically, and the tool 10 *T* is forced downwardly over the terminal *t*, the resiliency of the tool serving to spread the edges *e* and *e'* apart as the tool is moved downwardly over said terminal. Thereafter the tool may be rotated in a clockwise direction 15 as seen in Fig. 4, so that the cutting edge *e* will be resiliently held in engagement with the periphery of the terminal *t*, and serve to cut away the corroded substances and provide a clean surface for the reception of an 20 ordinary battery terminal connector, whereupon the tool may be removed by pulling the same upwardly and the resiliency of the tool will effect a complete restoration of the tool to normal shape.

25 Connectors such as are used on battery terminals are usually provided with bolts for frictionally holding the connectors on the terminals, and it is necessary in order to remove the same from or attach the same, to 30 remove or attach nuts, as at *N* in Fig. 3, from said bolts. It is desirable, therefore, that a tool for resurfacing the terminals should also be provided for removing and attaching said nuts, and to this end I provide on the jaws *J* and *J'*, respectively, of the plier members *A* and *A'*, cooperating and similarly formed nut 35 receiving portions which are provided internally with a series of serrations or notches *n*, *n*, etc. These notches are so arranged and disposed with respect to each other, and are of such size that the corners *l*, *l*, etc., of the nut will seat in the notches, while the facets 2, 2, etc., are disposed on lines as shown in Fig. 3.

40 Hexagonal nuts being common in use, the normal size and arrangement of the notches *m* is such that the corners *l*, *l*, etc., will engage certain of the notches when the nuts are in a certain position, and other of the notches when the nuts are in still other positions. 45 Thus, it will be observed that when the batteries are inaccessible or inconveniently positioned so as to afford access to the nuts, it is quite difficult, if not impossible, by the use of an ordinary wrench to move the nuts on the bolts, while the jaws *J* and *J'* formed as 50 shown, the notches *m* will engage the corners of the nuts irrespective of the particular position of a nut on a bolt, so that only a slight movement of the handles *H* and *H'* will be 55 necessary to remove the nut.

60 It will be understood, however, that the particular form of jaws *J* and *J'* are not material to the particular form of the tool *T*, and it is further conceived to be possible to 65 modify the form of the trimming tool from

that shown without departing from the spirit of my invention.

What I claim is:

1. A terminal trimming tool including a supporting member, a tool formed of spring steel, attached to said member, and provided with spaced edges, one of said edges being a cutting edge, and a bearing portion transversely opposite said edges, for receiving and trimming a battery terminal, as described. 70

2. A terminal trimming tool including a supporting member, a tool thereon formed of spring steel, and provided with spaced edges, one of said edges being a cutting edge, and a bearing portion opposite said edges, for receiving and trimming a battery terminal, said tool being tapered to conform to the taper of 75 said terminal. 80

3. A terminal trimming tool including a supporting member, a tool on one of said members formed of spring steel and provided with spaced edges, one of said edges being a cutting edge, said tool having a portion opposite said edges forming a bearing and arranged for receiving a battery terminal, said tool provided with an arcuately formed portion adjacent said cutting edge, and an attaching portion engaging and for attachment to said supporting member. 90

4. A terminal trimming tool embodying an integrally formed spring steel cutter having the ends thereof spaced apart for engagement with a battery terminal, one of said ends forming a cutting edge, a portion of the tool adjacent said cutting edge forming a bearing adapted to cooperate with said edges for trimming engagement with a battery terminal, as described. 95

5. A terminal trimming tool embodying an integral tapered metallic member having an arcuate terminal receiving portion terminating in a cutting edge, and an attaching portion with an edge spaced from said cutting edge, the side opposite said edges forming a bearing for operatively holding a terminal in engagement with the cutting edge. 105

6. A trimming tool comprising a handle, and a trimmer supported thereon and formed of spring steel for accommodation to different sizes of terminal parts, said trimmer having an attaching portion and an arcuate terminal receiving portion with edges spaced apart, one of said edges being a cutting edge, for trimming the periphery of a terminal when the tool is rotated. 115

7. A trimming tool for battery terminal posts comprising a handle, an integral spring steel tool attached thereto bent to form an attaching portion and a terminal receiving portion with its edges spaced apart, one of said edges being a cutting edge, the terminal receiving portion being yieldable relative to the attaching portion for accommodating the tool to terminals of different size. 125
